(57) CLAIM

We claim the ornamental design for a faucet handle, as shown and described.

DESCRIPTION

FIG. 1 illustrates a perspective view of a faucet handle showing a first embodiment of our new design;

FIG. 2 illustrates a top plan view of a faucet handle showing a first embodiment of our new design;

FIG. 3 illustrates a front elevational view of a faucet handle showing a first embodiment of our new design; and,

FIG. 4 illustrates a bottom plan view of a faucet handle showing a first embodiment of our new design.

The rear elevational view not shown is a mirror image of the front elevational view.
